UNITED STATES PATENT OFFICE.

DE FOREST B. CATLIN, OF BOSTON, MASSACHUSETTS.

DIATHERMIC APPARATUS FOR TREATMENT OF INTERNAL ORGANS ADJACENT TO THE RECTUM.

Application filed October 30, 1925. Serial No. 65,803.

This invention is embodied in certain improvements hereinafter described in apparatus for transmitting heating current from the rectum to the abdomen of the patient 5 through the post-urethral canal, the prostate gland, and other organs included in the region between the rectum and the abdomen.

Of the accompanying drawings forming a part of this specification—

10 Figure 1 shows a side elevation of a post-urethral electrode embodying the chief features of my invention, and an edge view of a supporting base for said electrode, an indifferent electrode and the region of the 15 body acted on by the apparatus being shown by broken lines, the figure showing also a diagram of the circuit connections.

Figure 2 is an end elevation of the post-urethral electrode shown by Figure 1.

20 The same reference characters indicate the same parts in all of the figures.

My improved post-urethral electrode hereinafter described, is usually known in diathermy as the "active" electrode, and is 25 used with a so-called "indifferent" electrode 12, placed upon the outer surface 13 of the abdomen. The electrode 12 is usually a plate of block tin, or other suitable metal, and has a surface area considerably greater 30 than that of the rectal portion of the active electrode. A binding post 14 on the electrode 12, is connected by a return conducting wire 15, with one pole of a generator 16, which may be a diathermy machine of any suitable 35 type.

The post-urethral or active electrode of my invention is made of any suitable conducting metal and includes a supporting portion 17, having a foot 18, adapted to 40 bear on a base 19 of insulating material, formed to be interposed between a supporting bed 20 and a surface portion 21 of the patient's body. The supporting portion is provided with means, such as a binding post 45 22, for connection with a supply wire 23.

When the apparatus is in use, the supporting portion 17 rises from the base 19, and is preferably inclined, as shown by Figure 1. The active electrode also includes an 50 elongated rectal portion 24, formed to enter the rectum 25, and extend from the anus 26 nearly or quite to the inner end of the rectum. The length of the rectal portion 24, the area of the electrode 12, and the po-

sition of the latter relative to the rectal 55 portion, are such that when the apparatus is in use, the post-urethral canal 27, the prostate gland 28, the bulb 29, and the vesicles 29^a shown by broken lines in Figure 1, are in the path of heating current 60 passing from the rectal portion to the electrode 12, as indicated by the substantially parallel lines in Figure 1.

The supporting portion 17, and the rectal portion 24, are rigidly connected and constitute a body or main portion. The active electrode preferably includes also a symphysis portion 30 of conducting metal, projecting upward from the electrode body at the outer end of the rectal portion 24. The portion 30 70 is formed and arranged to be interposed between a portion of the scrotum 31, and the adjacent portion 32 of the patient's body, extending between the scrotum and the anus.

The symphysis portion is preferably 75 hinged at 33 to the body of the active electrode, so that it may stand at various angles relative to the rectal portion 24. A biasing spring 34, fixed at 35 to the body of the active electrode, has a free end bearing on 80 the symphysis portion 30, and adapted to press the latter against the surface 32.

The surface area and position of the indifferent electrode 12 determine the location 85 of the greatest temperature.

In this instance the arrangement is such that the temperature is highest in the regions of the post-urethral canal, the bulb, the vesicles, and the prostate gland.

The symphysis portion 30 directs heating 90 current across that part of the post-urethral canal which extends approximately parallel with the body surface 32 on which the portion 30 bears, and ensures more effective 95 treatment of this canal part than is afforded by current emanating from the rectal portion 24.

The base 19 may be provided with means 100 engaging the foot 18 of the supporting portion 17, to prevent displacement of the active electrode from the operative position shown by Figure 1, said means having preferably embodied in a cleat 38, bearing on the outer edge of the foot. As above stated, the base 19 is confined by the weight of the 105 body portion bearing thereon, so that the cleat constitutes a practically fixed abutment, preventing movement of the active

electrode tending to withdraw the rectal portion 24 from the rectum.

The rectal portion is provided with a longitudinal socket 39, closed at the inner end and open at the outer end. In the socket is inserted a thermometer including a graduated tube 40, which is visible at the outer end of the rectal portion, the usual bulb 41 of the thermometer being at or near the inner end of the rectal portion. The thermometer indicates to a physician the approximate temperature of the parts under treatment, and enables him to properly control the temperature.

15 It will now be seen that the described apparatus is adapted to treat diseased organs, or parts of the human body, by generating a high degree of heat within the tissues, for the purpose of relieving inflammation and 20 congestion, killing germs of disease, particularly in the post-urethral canal, and producing other useful results. Due to the high temperature, a very large amount of blood is forced through the arteries, so that a localized fever is produced, which is taken 25 care of by the general circulation, within a short time after treatment.

I claim:

1. In diathermic apparatus of the character stated, a post-urethral active electrode comprising a supporting portion, formed to bear on and project upward from a support below a patient's body and provided with means for connection with a conductor, 35 and an elongated rectal portion arranged at an angle with the supporting portion and formed to enter the rectum, the arrangement being such that heating current may pass from the rectal portion through the prostate 40 gland, the post-urethral canal, and other or-

gans, to an indifferent electrode placed on the abdomen.

2. In diathermic apparatus of the character stated, a post-urethral active electrode comprising a supporting portion, formed to bear on and project upward from a support below a patient's body, and provided with means for connection with a conductor, an elongated rectal portion arranged at an angle with the supporting portion and formed 50 to enter the rectum, said supporting and rectal portions forming an angular electrode body; and a symphysis portion projecting upward from the electrode body, and formed and arranged to be interposed between a portion of the scrotum and an adjacent surface of the patient's body.

3. In diathermic apparatus of the character stated, a post-urethral active electrode comprising a supporting portion, formed 60 to bear on and project upward from a support below a patient's body, and provided with means for connection with a conductor, an elongated rectal portion arranged at an angle with the supporting portion and formed 65 to enter the rectum, said supporting and rectal portions forming an angular electrode body; and a symphysis portion projecting upward from the electrode body, and formed and arranged to be interposed between a portion of the scrotum and an adjacent 70 surface of the patient's body, the symphysis portion being hinged to the electrode body and provided with a biasing spring whereby it is pressed yieldingly against said adjacent 75 body surface.

In testimony whereof I have affixed my signature.

DE FOREST B. CATLIN.
